UNITED STATES PATENT OFFICE.

NORMAN HOWARD, OF YONKERS, NEW YORK.

DULCET ATTACHMENT FOR BANJOS.

No. 821,494.

Specification of Letters Patent.

Patented May 22, 1906.

Application filed February 23, 1906. Serial No. 302,545.

To all whom it may concern:

Be it known that I, NORMAN HOWARD, a citizen of the United States, residing at Yonkers, in the county of Westchester and State 5 of New York, have invented certain new and useful Improvements in Dulcet Attachments for Banjos; and I do hereby declare the following to be a full, clear, and exact description of the invention, such as will enable others skilled in the art to which it appertains to 10 make and use the same, reference being had to the accompanying drawings, and to the letters of reference marked thereon, which form a part of this specification.

15 This invention relates to new and useful improvements in dulcet attachments for banjos, and comprises a simple and efficient device which may be attached to the bridge only of the instrument without contact with 20 the head, whereby the tones of the instrument may be softened, whereas with the devices of this nature heretofore used contact is made with the vibrating parchment forming the head, which deadens the tone, as the head 25 constitutes the sounding-board.

My invention consists, further, in various details of construction and arrangements of parts, which will be hereinafter fully described and then specifically defined in the appended 30 claims.

I illustrate my invention in the accompanying drawings, which, with the letters of reference marked thereon, form a part of this application, and in which—

35 Figure 1 is a side elevation of a banjo, showing the application of my invention. Fig. 2 is a vertical sectional view through the head and attachments, parts being shown in elevation. Fig. 3 is an enlarged detail perspective view of the device, and Fig. 4 is a perspective view showing the attaching means for holding the dulcet.

40 Reference now being had to the details of the drawings by letter, A designates the frame of the head of the banjo, over which is strung the parchment B, which is held in a taut relation by means of the rods C, having the tightening-screws D.

45 E designates the bridge of the instrument, 50 over which the strings F pass, and G designates a tailpiece having an angled end slotted to receive the ends of the strings.

H designates a bracket-arm, which is shown in section in Fig. 2 of the drawings as being 55 held to the reinforced frame by means of a screw I and is apertured to receive the thread-

ed rod K. Said rod has a shoulder K' integral therewith, and one end is bent to form a hook N. (Shown clearly in Fig. 3 of the drawings.) Said rod is passed through an aperture in the end of the tailpiece, which latter bears against the shoulder K' and is afterward passed through the aperture in the bracket-arm H and held in an adjusted position by means of a screw O, fitted upon the threaded rod.

Q designates a strip, preferably of wood of any kind, which has a transverse aperture at one end to receive the hooked end N of said rod K in the manner shown clearly in Fig. 3 70 of the drawings, and the forward end of the wooden strip Q has a lateral projection Q', having a transverse recess Q², which is intersected by a recess Q³. (Shown clearly in the perspective view, Fig. 3.) Said transverse 75 recess Q² is provided for the purpose of receiving the bridge E, while the space Q³ is afforded to allow one of the strings of the banjo to pass therethrough.

In applying my device, the tailpiece being 80 adjusted in the manner shown, being held against the shoulder K by the tightening-nut K', the strip Q is caught over the hook N and fulcrumed over the tailpiece in the manner shown in Figs. 1 and 2 of the drawings, and 85 the laterally-projecting portion Q is pushed down over the bridge in the manner shown in Figs. 1 and 2 and made to bind against the bridge without contact with the vibrating parchment head, thereby softening the tone 90 of the instrument without deadening the same, as would be the case if the end of said lateral projection came into contact with the parchment.

From the foregoing it will be noted that by 95 the provision of the apparatus shown and described a simple and efficient means is afforded which may be easily and quickly attached to the instrument to produce the softening of the tone and at the same time affording an 100 ornamental attachment.

What I claim is—

1. In combination with a banjo having a head and bridge thereon, a tailpiece to which the strings of the instrument are held, a threaded rod engaging said tailpiece, whereby the latter may be held to the frame of the head, a tone-softening attachment pivotally connected to said rod and having a lateral projection which is slotted and adapted to 105 frictionally engage said bridge, as set forth.
2. In combination with the head of a banjo

and frame therefor, a bridge, a bracket-arm fixed to said frame, a threaded rod passing through an aperture in said arm, an adjusting-screw upon said rod, a tailpiece connecting-screw upon said rod, one end of said rod bent to form a hook, a tone-softening attachment having an aperture at one end to receive said hook, and a lateral projection which is slotted and adapted to frictionally engage said

10 bridge, as set forth.

3. In combination with the head of a banjo, and frame therefor, a bridge, a bracket-arm fixed to said frame and provided with an aperture, a threaded rod passing through the

15 aperture of said arm, a tightening-nut upon said rod adapted to bear against said arm, a

tailpiece having an aperture to receive said rod, a shoulder upon said rod and a tightening-nut adapted to hold the apertured end of said tailpiece against said shoulder, and a

20

25

tone-softening strip having an aperture to receive the hooked end of said rod, a lateral projection of said strip having intersecting recesses and adapted to frictionally engage the bridge of the banjo, as set forth.

In testimony whereof I hereunto affix my signature in the presence of two witnesses.

NORMAN HOWARD.
